UNITED STATES PATENT OFFICE.

RAYMOND H. BAKER, OF NEW YORK, N. Y., ASSIGNOR TO TAYLOR-WHARTON IRON AND STEEL COMPANY, OF HIGH BRIDGE, NEW JERSEY, A CORPORATION OF NEW JERSEY.

BALL-MILL LINING.

Application filed January 31, 1923. Serial No. 616,076.

To all whom it may concern:

Be it known that I, RAYMOND H. BAKER, a citizen of the United States, residing at New York, in the county of New York and 5 State of New York, have invented certain new and useful Improvements in Ball-Mill Linings, of which the following is a specification.

The linings of grinding mills which utilize 10 balls, pebbles and kindred fugitive grinding elements, are subject to rapid wear and must be renewed or replaced from time to time. With present linings this is more or less of an awkward proceeding entailing 15 much time and labor.

Objects of my invention are to provide a lining of high efficiency; to provide a lining of simple construction and which will outlast any lining heretofore proposed; to provide 20 a lining which will remain tight under all conditions of service; to provide a lining including main wear resisting elements in the form of rails; to provide a lining of the character specified in which the rails, 25 including head and base, are solid and of considerable depth; to provide a lining of the character specified in which the base flanges of the rails co-operate with adjustable locking provisions; to provide a lining 30 of the character specified in which the locking provisions are of such nature as to provide for uniform spacing of the rails and eventual joint wear with the rails; to provide a lining of the character specified 35 in which the heads of the rails overhang the intermediate locking bar and temporarily guard the same during the assemblage of the parts; to provide a lining of the character specified in which, after the 40 heads of the rails are worn away, the remainder, consisting of rail bases and locking bars, will wear uniformly actually to the shell; and to provide a rail lining such as indicated whereof the rails are so formed 45 and so co-related as to provide trapping areas for trapping ore or other material undergoing grinding which accordingly takes some of the wear and so prolongs the life of the lining.

With such and other objects in view, the nature, characteristic features and scope of the invention will more readily be understood from the following description

taken in connection with the accompanying drawing, forming a part hereof, wherein,— 55

Figure 1 is a fragmentary cross-sectional view of a lining embodying my invention; and

Fig. 2 is a perspective view of one of the rails and its complemental locking and spacing bar in detached relation. 60

According to my invention rails in spaced relation are disposed in parallelism with their bases bearing upon the inner wall of the shell or drum and with their heads exposed to take the brunt of the grinding, the rails being uniformly spaced and properly anchored by a simple and convenient means of adjustment. 65

The rails, which may be cast, or forged 70 as by rolling, are preferably constructed of manganese steel or other wear resisting steel, with a substantially large head 5 and a broad bearing base 6. The tops of the rails are flat and present considerable surface area for grinding purposes. The sides extend vertically a short distance and are then inwardly directed to where they join the base. The latter has flanges 7 the side walls of which are beveled as at 8. 75

Co-operating with the rails for properly spacing and locking them are wedge elements consisting of plates or bars 9 with lateral bevels 10 corresponding to the beveled flanges of the rails. The bars 9 have countersunk bolt holes 11 to accommodate the locking bolts 12 which extend through the shell 13 and are secured by nuts 14. Evidently, by tightening up on the nuts the wedge elements 9 will bear down 80 upon the rail flanges and maintain the proper spacing and rigidity of the rails essential for efficient grinding. The adjusting plates or elements 9 are substantially the thickness of the base flanges and 85 when fully seated their tops are flush with the tops of the flanges. It will be noted that the heads of opposite rails overhang the plates 9 and this is of advantage in the assemblage of the parts in the temporary 90 support of said plates. 95

The rails are so co-related with respect to their lateral shapes that the spaces between them afford means for trapping ore or other material undergoing grinding which, without interfering with the adjusting means, 100 105

becomes tightly packed or wedged between the rails and thus shares some of the wear and so prolongs the life of the lining.

Since the rails are mates and the locking 5 bars are likewise mates, the lining is structurally simple and can be assembled with little loss of time and labor.

The rails being of considerable depth and grinding surface area will wear comparatively slowly and even when the heads 10 are completely worn away the lining will still function for an appreciable period owing to the fact that the rail bases are solid or intact and will wear uniformly with the 15 locking bars all the way to the shell.

Having described my invention, I claim:—

1. In combination with the shell of a grinding mill, separable lining elements of 20 substantial keystone shape in cross section, the extended bases of which are arranged

in contact with the shell, with the narrower portions of substantial depth and thickness, and means cooperating with the edges of adjacent bases for securing said linings in 25 place, said means having wedging engagement with such bases and presenting substantial continuations of such bases when the parts are assembled.

2. In combination with a shell of a grinding mill, longitudinally arranged independent lining elements having broad bases with undercut walls, and bars with edges to cooperate with and exert wedging action on such undercut walls, said bars being 30 35 removably secured between adjacent lining elements, and forming practical continuation of such bases when in securing relation to the shell.

In testimony whereof I affix my signature. 40

RAYMOND H. BAKER.
